SAFETY RAZOR

Filed March 31, 1927.

Inventor
John Reid
Knight, Brown, Quincy, May
Attn: S.

UNITED STATES PATENT OFFICE.

JOHN REID, OF BOSTON, MASSACHUSETTS.

SAFETY RAZOR.

Application filed March 31, 1927. Serial No. 179,884.

This invention relates to the blade-holding body and handle of a safety-razor, the body including a guard plate and a clamping plate adapted to operatively confine a normally flat resilient blade, such as the Gillette, and impart a transverse curvature to the blade when they are adjusted to clamp the latter.

One object of the invention is to provide an improved construction of the guard and clamping plates, whereby they may be quickly and conveniently assembled and separated without the employment of screw threads, the construction being such that the said plates and the means for clamping them on the blade may be composed entirely of two sheet metal parts, and manufactured at a minimum cost, no lathe and screw-thread cutting work being involved.

Another object is to provide a folding razor or blade-holding body including a handle composed also of two sheet metal parts, made entirely without lathe and screw-cutting work, the members being foldable against the body of the razor, and forming an operative angular handle projecting from the body when adjusted for use, the members of the handle being slidably and inseparably connected.

Of the accompanying drawings forming a part of this specification,

Figure 1 is a side view of a safety-razor embodying the invention.

Figure 2 is a section on line 2—2 of Figure 1.

Figure 3 is a section on line 3—3 of Figure 1.

Figure 4 is a view similar to Figure 3, showing the blade in its normal flat form and the clamping plate supported in a raised position by the blade.

Figure 5 is an end view of the razor.

Figures 6 and 7 are perspective views showing the handle members separated from the razor body and from each other.

Figure 8 is a view similar to Figure 1, showing the parts in the relative positions shown by Figure 4.

Figure 9 is a fragmentary perspective view, showing a portion of the guard plate,

Figure 10 is a fragmentary perspective view, showing a portion of the clamping plate.

The same reference characters indicate the same parts in all of the figures.

In the drawings, 12 designates a trans-

versely curved guard plate of sheet metal, having guards at its opposite longitudinal edge portions, preferably formed by cutting lather-conducting slots 13, the slots being separated by narrow bars 14, constituting the equivalent of the usual comb teeth with which a guard plate is provided.

The guard plate is provided at its opposite ends with holding-down coupling members, adapted to hold down the clamping plate hereinafter described, and preferably formed by upstanding ears 15 and 16, integral with the plate. Each ear includes a neck portion 160 and shoulders 17 overhanging the ends 70 of the neck portion. The guard plate and its integral coupling members constitute a single piece of sheet metal.

The guard plate forms a seat adapted to support a flattened resilient blade 18 of the Gillette type, with its cutting edges raised above the seat, as shown by Figure 4. 19 designates a transversely curved clamping plate formed to bear on the flattened blade, the arrangement being such that when the blade is flat, and the clamping plate is deposited thereon, said plate is elevated above the shoulders 17, as shown by Figure 4. When the clamping plate is thus deposited on the blade, it is in the inoperative position shown by Figure 8, and is movable sidewise from said position to curve the blade against the guard plate, as shown by Figure 3. The clamping plate is provided with complementary coupling members engageable with the holding-down members 15 and 16 on the guard plate, by an endwise movement of the clamping plate to the operative position shown by Figure 1. One of said coupling members is preferably embodied in an angular orifice 20, in one end portion of the clamping plate, said orifice including a wider portion 21, formed to receive the holding-down member 16, as shown by Figure 8, and a narrower portion 22, the ends of which are adapted to be moved under the shoulders of the member 16, as indicated by Figure 1. The other of said coupling members is preferably embodied in an open recess 23, having inclined ends 24. 105

When the clamping plate is in the position shown by Figure 8, the recess ends 24 are adapted to be moved under the shoulders of the holding-down member 15, as indicated by Figure 1. The coupling members on the clamping plate are integral parts thereof, so that the clamping plate and its coupling

members are composed of a single piece of sheet metal.

In assembling the parts, the flat blade is first deposited on the guard plate and is positioned thereon by sheet metal ears or studs 26, integral with and struck up from the guard plate and formed to enter the usual orifices 27 (Figures 1 and 2) in the blade. The clamping plate 19 is then deposited in the position shown by Figure 8, on the flattened blade, and is supported by the latter above the shoulders 17, as shown by Figure 4. The operator next presses the clamping plate sidewise inwardly, to curve the blade 15 against the guard plate, and then moves the clamping plate endwise to the position shown by Figure 1, thus engaging the ends 22 of the orifice 20, with the overhanging shoulders of the holding-down member 16, 20 and the ends 24 of the recess 23, with the overhanging shoulders of the holding-down member 15, so that the blade is operatively clamped between the guard plate and the clamping plate, the blade being tensioned, 25 so that in its effort to assume its normal form, it exerts sufficient frictional pressure on the clamping plate to prevent accidental movement of the latter to the blade-releasing position shown by Figure 8. Such movement may be easily caused by pressure of the operator's finger or thumb on a roughened portion 30 of the clamping plate, in the direction of arrow X in Figure 1.

The clamping plate 19 is provided with longitudinal slots 31, receiving the studs 26 and permitting the described endwise movements of the clamping plate.

I provide the razor body with a handle composed of two members 32 and 33, preferably of sheet metal and formed as shown by Figures 6 and 7. Said members are hinged at their inner ends to the opposite ends of the guard plate, preferably by sheet metal hinge sockets formed by bent ears 34 integral with the guard plate and projecting inwardly therefrom, and sheet metal hinge pintles or trunnions 35, integral with the handle members and engaged with said sockets to turn therein.

The handle members are provided with adjustable connecting means between their inner and outer ends, permitting the folding of the members as indicated by dotted lines in Figure 2, and their movement from the folded positions to form an angular handle, projecting from the guard plate, as shown by full lines, the handle members and the guard plate forming an angular opening in which a fore finger may be inserted, 60 to bear on the inner sides of the members, the thumb and second finger bearing at the same time, on the outer sides of the members.

The said adjustable connecting means, in this instance, is provided by the edges of

a longitudinal slot 36, formed in the member 32, and a T-shaped outer end portion 37, formed on the member 33 and slidable in the slot. The end portion 37 is bent from the plane of the member 33, and extends 70 through the slot. The outer end 38 of the slot constitutes a stop, limiting the outward sliding movement of the end portion 37, and preventing the separation of the handle members from each other, when said members are hinged to the guard plate. In practice the member 33 will be folded closely against the guard plate, and the member 32 will be folded closely against the member 33. The dotted line representation in Figure 2 is intended to show the handle members incompletely folded. The T-shaped end portion 37 is continuously engaged with the edges of the slot 36, so that it is slidably and inseparably engaged with the member 32.

The drawings show the parts enlarged to about twice their actual size. When the razor is folded, it is extremely compact and may be carried in a vest pocket, or hung on 90 a watch chain, by a split ring engaged with a notch 40, in one edge of the orifice 20.

I claim:

1. A safety razor comprising a transversely curved guard plate having guards 95 at its opposite edges, upstanding holding-down ears at its opposite ends, each including a neck portion and oppositely projecting shoulders overhanging the ends of the neck portion, the plate constituting a seat adapted to support a flattened resilient blade, with 100 its cutting edges raised from the seat, and a clamping plate formed to bear on the flattened blade and movable sidewise to curve the blade against the guard plate, and endwise to operatively confine the blade, the 105 clamping plate having in one end an angular aperture including a wider portion, formed to receive one of said ears, and a narrower portion, formed to receive the neck portion 110 of said ear, and in its opposite end an open recess formed to receive the neck portion of the other ear, the arrangement being such that when the blade is flattened, and the clamping plate is deposited thereon, the 115 clamping plate is movable first, sidewise to curve the blade on the guard plate, and locate the recess and aperture of the clamping plate below the shoulders of the ears, and then endwise to locate the ends of the 120 recess under the shoulders of one ear, and the narrower portion of the orifice under the shoulders of the other ear, so that the razor is rendered operative, and the clamping plate is confined against endwise movement from its operative position by the effort of the blade to assume its normal flat form.

2. A foldable safety razor, comprising a body including a guard plate, a clamping plate, and means for confining the clamping 130

plate on a blade interposed between the plates, the guard plate being provided with hinge sockets, and a handle including two members having hinge pintles at their inner ends, engaging said sockets, to permit swinging movements of the members in opposite directions inwardly toward the guard plate, and thereby fold the razor, and in opposite directions outwardly from the guard plate, to form an angular handle, one member being provided with a longitudinal slot whose outer end forms a stop, the other member having a bent T-shaped outer end portion continuously engaged with the edges of the slot, and slideable therein and abutting said stop when the members are adjusted to form an angular handle, the T-shaped end portion being inseparable from the slotted member and abutting said stop when the members are adjusted to form an annular handle.

3. A foldable safety-razor, the blade-holding body of which is composed entirely of sheet metal and is adapted to flex and operatively confine a blade of the Gillette type, said body comprising a transversely curved one-piece sheet metal guard plate formed to support a flattened blade, and having guards at its opposite longitudinal edges, holding-down coupling members at its opposite ends, and sheet metal hinge sockets projecting

from the inner side of the plate, all integral with the plate, a one-piece sheet metal clamping plate formed to bear on a flattened blade, and movable sidewise to flex the blade, and endwise to operatively confine the flexed blade, the clamping plate having complementary coupling members integral therewith and engageable with the holding-down members by an endwise movement of the clamping plate, and a handle including two sheet metal members, having sheet metal hinge pintles at their inner ends, engaging said sheet metal sockets to permit swinging movements of the members in opposite directions inwardly toward the guard plate, and thereby fold the razor, and in opposite directions outwardly from the guard plate to form an annular handle, one member being provided with a longitudinal slot whose outer end forms a stop, the other member having a bent T-shaped outer end portion continuously engaged with the edges of the slot and slideable therein, and abutting said stop when the members are adjusted to form an angular handle, the T-shaped end portion being inseparable from the slotted member.

In testimony whereof I have affixed my signature.
